UNITED STATES PATENT OFFICE.

JAMES M. SMITH, OF NEWARK, NEW JERSEY, ASSIGNOR TO JESSE WALRATH, OF RACINE, WISCONSIN.

ELECTRIC IGNITING DEVICE FOR EXPLOSIVE-ENGINES.

SPECIFICATION forming part of Letters Patent No. 691,498, dated January 21, 1902.

Application filed December 21, 1899. Serial No. 741,087. (No model.)

To all whom it may concern:

Be it known that I, JAMES M. SMITH, a citizen of the United States, residing at Newark, in the county of Essex and State of New Jersey, have invented certain new and useful Improvements in Explosive-Engines; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in explosive-engines in which a gas or vapor, such as is obtained from gasoline or the like, is caused to be ignited by means of an electric spark and by expansion operates upon the piston or plunger in the cylinder, and thereby actuates the working parts of the engine.

My present invention therefore primarily consists in the novel construction of engine-cylinder, a novel arrangement and combination therewith of an igniting or sparking means for exploding the gas or vapor, and a novel system of passages in the cylinder whereby provision is made for the complete expulsion of the compressed air or gas from the cylinder during the upward stroke of the piston.

My invention, furthermore, consists in a novel igniting or sparking means for exploding the gas or vapor, the parts of said mechanism being preferably adjustable, whereby an electric spark can be produced at different positions of the piston on its return stroke, causing the exploded gas to act with greater or less expansive force against the piston, whereby the movements of the latter are regulated and the engine made to run fast or slow.

The invention consists, further, in a novel means for causing the igniting or sparking means to operate in proportion to the relative movements of the piston—that is, whereby the piston can be made to make two (or more) complete up-and-down strokes while the igniting or sparking means is actuated only once; but of course this proportion may be

desirably varied according to existing conditions.

My invention is clearly illustrated in the accompanying drawings, in which—

Figure 1 is a side view of an explosive-engine to which the sparking-igniter embodying the principles of my invention is applied. Fig. 2 is a side view of a ring or collar and spring-actuated trip pawl or dog used in connection with the igniting or sparking mechanism, and Fig. 3 is a cross-section of the same. Fig. 4 is a vertical section on line 77 in Fig. 5 of a bearing for the reception of the igniting or sparking spindles or rods, and Fig. 5 is a face view of the said bearing. Figs. 6 and 7 are two side views of the said sparking or igniting spindles. Fig. 8 is a longitudinal vertical section of a pivoted casing and spring-dog, forming a portion of the said sparking mechanism. Fig. 9 is an end view of the same, and Fig. 10 is a vertical cross-section taken on line 13 13 in said Fig. 8. Fig. 11 is a detail section of the upper portion of a rod to be connected with the parts represented in said Figs. 8, 9, and 10, representing a bumper arrangement constructed to counteract or reduce the strain on a connecting-link of the said sparking or igniting means; and Fig. 12 is a top view of the said parts represented in said Fig. 11. Fig. 13 is a horizontal cross-section taken on line 16 16 in Fig. 11, and Fig. 14 is a similar section taken on line 17 17 in said Fig. 11.

Similar letters of reference are employed in all of the said above-described views to indicate corresponding parts.

In the said drawings, *b* indicates the usual construction of crank-shaft, which is mounted and rotates in the usual bearings of a suitable framework or support *b*². As will be seen from an inspection of Fig. 1, the top or bed portion *b*¹ of the framework or support *b*² has secured thereon the explosion-cylinder *a* of the engine. The cylinder *a*, as will be seen from Fig. 1, has an upper flange *a*³, upon which is secured the upper cylinder-head *c*, said cylinder having a lower flange *a*² resting upon the bed portion *b*¹ and secured in place by means of bolts or set-screws *a*⁶, substantially as illustrated. At the back the cylinder has an exhaust-chamber *a*⁷, with which is con-

nected a suitable exhaust-pipe f , and at or near the top of the cylinder, in one side thereof, is an opening a^8 , as illustrated more particularly in Fig. 4, and in which I have secured a bearing d , as and for the purposes to be hereinafter more fully set forth.

On its outer surface the cylinder a is preferably formed with annular ribs or projections a^9 , of any desirable shape and number, 10 with suitable annular depressions a^{10} between said ribs or projections, as clearly illustrated. This arrangement of the ribs or projections is to produce sufficient strength to withstand the explosive force within the cylinder, and 15 the intermediate depressions are for the purpose of reducing the thickness of metal of the cylinder, and thereby greatly reducing the possibility of the cylinder becoming overheated when the engine is in constant use, as 20 will be clearly understood.

The cover c is provided with the usual form of stop-cock g or other suitable blow-off. An inlet-pipe e and an eduction-pipe f' are secured in position to the sides of said head c , 25 substantially as shown. The said pipe f' may be connected, by means of suitable fittings f^3 and f^4 and the pipe f^5 , with the exhaust-pipe f , as shown. Connected with said inlet-pipe e in any well-known manner is a suitable carbureting device h , which is provided with an inlet h' .

Suitably secured upon the crank-shaft b is a toothed pinion m , which is in operative mesh with a gear-wheel n , rotatively arranged 35 in any well-known manner on a pin or stud n' , extending from the side of the framework or support b^2 . Secured upon the hub of said gear-wheel n is a collar o and a collar p , which has a cam-shaped extension or teat p' , as 40 clearly indicated in dotted outline in Fig. 1 of the drawings. This teat p' during the revolutions of the collar p actuates an arm s' , which is pivotally connected with a rod s for operating the usual form of exhaust or relief 45 valve arranged within the cylinder-head c .

The cam-ring p is placed in such a manner that the exhaust-valve is opened during the upward movement of the piston of the engine, while the inlet-valve is closed, as will be 50 clearly understood.

In order that the vaporized or carbureted gasolene or other suitable gas after it has been properly admitted into the upper portion of the cylinder a may be properly exploded and cause an expansive pressure upon the piston to move it downwardly, I have arranged in the bearing d , previously mentioned, a sparking or igniting device, which is properly operated and actuated from a 55 spring-dog o' , connected with the collar o on the hub of the gear-wheel n .

As will be seen from Figs. 4 and 5, the bearing d is properly secured in an opening a^8 in the side of the upper portion of the cylinder a , having a tubular duct d' and a duct d^2 , in which there is a collar d^3 of an insulating material. Operatively arranged in said duct

d' , so as to be capable of an oscillatory motion therein, is a sparking or igniting stem d^4 , said stem being preferably provided with a 70 conical shoulder d^6 , which fits a conical recess d^7 in the bearing d to produce a close and positive contact. Extending into the opening a^8 directly back of the bearing is a part d^5 of said stem d^4 , said part having a 75 short arm or projection d^8 , which is preferably provided with a contact-piece d^9 . The opposite end d^{10} of said stem d^4 extends through the said bearing d and has secured thereto a connecting-arm u , which is connected with a 80 connecting rod or link t , to be actuated from said spring-dog o' , as will hereinafter be made clear. Within said insulating-collar d^3 , in the duct d^2 of the bearing d , is a second stem d^{11} , said stem being held in said collar 85 d^3 by a shoulder d^{12} and one or more nuts d^{13} on the screw-threaded end d^{14} of said stem d^{11} . The said stem d^{11} also has a part d^{15} , which extends into the opening a^8 back of the bearing d and is provided with a short 90 arm or projection d^{16} , which may be provided with a contact-piece d^{17} and establishes an electrical circuit with the contact-piece d^9 when these parts touch, as indicated in dotted outline in Fig. 1, and when an electric current is passed through a wire w , connected with the stem d^{11} by means of the nuts d^{13} , into the stem d^4 and then through the cylinder a to and through a wire w' from a battery or other source of electrical energy with 95 which said wires are connected. To break the electrical contact between the contact-pieces of the stems d^4 and d^{11} , I have suitably secured the end u' of the arm u upon the end d^{10} of the stem d^4 to cause a vibratory 100 motion of the piece d^8 when said arm is made to oscillate by the upward and downward movements of a rod t , substantially as and in the manner hereinafter more fully set forth. The opposite and ring-shaped end u^2 of said 105 arm u is loosely arranged upon an enlargement v' of a sleeve v , provided with an internal screw-thread v^2 for securing said sleeve upon the upper and screw-threaded end t' of the link or rod t , said end u^2 of the arm u being movably but operatively supported upon 110 said enlargement v' by a loose collar v^3 on the sleeve v and a nut v^4 , which is screwed upon an external screw-thread upon the upper portion of said sleeve v and against the resiliency 115 of a coiled spring v^5 , which surrounds said sleeve v , and is held in position by said collar v^3 and said nut v^4 , as clearly illustrated in the several figures of the drawings. The lower end t^2 of said rod or link t is provided 120 with a shoe t^3 or other suitable means provided with a screw or pin t^4 for pivotally connecting said end of the rod t with a box or casing x , having a tubular hub or bearing portion x' for pivotally arranging said box or 125 casing upon a pin or stud z , extending from the side of the frame portion or support b^2 . Said box or casing is held in its normal position (indicated in Fig. 1) by a split collar 130

5 *y*, secured on the hub of said box, said collar having an arm *y*² and a spring, as *y*', connected therewith and with the support *b*³ for normally forcing said arm *y*² against a pin or projection *b*³, as clearly indicated. Said box or casing *x* is preferably of a rectangular shape and has secured upon its open top and extending down one end thereof a cover *x*², which is provided in its downwardly-extending end piece *x*³ with a hole *x*⁴. Said cover may also be provided with a recess *x*⁵. Slidably arranged within said box or casing *x* is a lift-dog *x*⁶ and a rod or stem *x*⁷, connected therewith, said dog *x*⁶ extending at its end *x*⁸ 10 from the open end of the box or casing *x* and a screw-threaded end *x*⁹ of the rod or stem *x*⁷, projecting through the hole *x*⁴. On said screw end of the rod or stem *x*⁷ is a finger-piece *x*¹⁰, movably arranged thereon for proper 15 adjustment of the end *x*⁸ of the lift-dog *x*⁶ from the casing *x* against the action of a coiled spring *a*¹¹, encircling the stem *x*⁷ within the box or casing *x*, as shown in Fig. 8. The said finger-piece *x*¹⁰ may also be provided with a rearwardly-extending pin *x*¹², which can be made to project into said recess *x*⁵ or against the outer surface of the end piece *x*³, whereby the free end *x*⁸ of the lift-dog *x*⁶ can be quickly brought closer toward 20 or farther away from the central vertical axial line of the cylinder *a* without first manipulating the finger-piece *x*¹⁰. In this manner when the parts of the machine move in the direction of the arrow in Fig. 1, the spring-dog *o*' 25 of the collar *o* can be brought in quicker or slower lifting engagement with the lift-dog *x*⁶, whereby the respective contact-pieces of the stems *d*¹ and *d*¹¹ may be made to break electrical contact while the piston is still some distance 30 from the upper part of the cylinder *a* or when the piston has nearly reached the top of the cylinder, as might be the case, according to the position of the said pin *x*¹². Thus an electric spark may be caused sooner or later by the 35 breaking of the circuit-contacts and the piston-rod will make slower or faster revolutions, whereby the speed of the engine is varied at will and all owing to the earlier or later explosion of the gas in the upper portion of the 40 cylinder *a*.

50 As shown in the several figures of the drawings, the lifting-dog *o*' has a flat surface *o*³, which is brought against the flat surface of the end *x*⁸ of the lift-dog *x*⁶, a spring *o*² being 55 employed to at all times retain said dog *o*' in its operative position for engagement with the end of the dog *x*⁶. In case of any backward movement of the dog *o*' the spring *o*² will permit the dog *o*' to slide over the bevelled part of the end *x*⁸ of the lift-dog *x*⁶ without actuating the rod *t*, and hence there will be no accidental actuation of the sparking-igniter, as will be clearly evident.

60 The operations of the several mechanism 65 will be clearly evident from the accompanying drawings and the above description, the pinion *m* and gear *n* being constructed in the

proportion of two to one, so that the pinion *m* makes two revolutions to one of the gear *n*, whereby the gas is exploded only during each second return of the piston; but of course it will be understood that said gears may be of the same diameters or the proportions of the same may be varied from that herein set forth.

75 The operation of the engine in general is as follows: During the first downstroke of the piston the latter draws a charge of air into the cylinder. At the same time the air is being drawn into the cylinder a small amount of gasolene is being admitted through the vaporizer or carbureter into the induction-valve. On the upstroke of the piston the gas formed is compressed in the top of the cylinder, and when the piston is near the end of the upstroke this charge is ignited by the electric spark and the piston is driven down by the force of the expanding gas. When the piston is near the end of its downstroke, owing to the general arrangement of the several mechanism, the exhaust-valve is opened and remains open until the end of the upstroke, expelling all burned gases. This is repeated during every second revolution, owing to the ratio of the gears *m* and *n*, hereinabove 95 mentioned.

Having thus described my invention, what I claim is—

1. In an explosive-engine, the combination with the igniter mechanism, of a pivoted arm 100 having its movable end operatively connected with said igniter mechanism, an igniter-operating cam, an adjustable part having a sliding engagement with said arm, adapted to engage said cam, and means for securing said part at different longitudinal positions on said arm, substantially as and for the purposes set forth.

2. In an explosive-gas engine, the combination, with a cylinder, crank-shaft, and piston, of a bearing device in one side of the cylinder, having tubular openings, a fixed or stationary igniting-stem in one of said openings, but insulated from said bearing, an oscillatory igniting-stem in the other of said 115 openings in said bearing, contact-pieces connected with said stems, and means connected with said oscillatory igniting-stem for producing a rock motion of the same, consisting, essentially, of an arm or lever *u* having one end 120 attached to the free end of said oscillatory stem, a downwardly-extending rod or link *t*, with which the opposite end of said arm or lever *u* is operatively connected, an oscillatory casing to which the lower end of said 125 rod or link *t* is attached, a spring-actuated lift-dog slidably arranged in said casing having a portion extending therefrom, and means operated from the crank-shaft and engaging with said lift-dog for actuating said oscillatory igniting-stem, substantially as and for the purposes set forth.

3. In an explosive-gas engine, the combination, with a cylinder, crank-shaft, and pis-

ton, of a bearing device in one side of the cylinder, having tubular openings, a fixed or stationary igniting-stem in one of said openings, but insulated from said bearing, an oscillatory igniting-stem in the other of said openings in said bearing, contact-pieces connected with said stems, and means connected with said oscillatory igniting-stem for producing a rock motion of the same, consisting, essentially, of an arm or lever *u* having one end attached to the free end of said oscillatory stem, a downwardly-extending rod or link *t*, with which the opposite end of said arm or lever *u* is operatively connected, an oscillatory casing to which the lower end of said rod or link *t* is attached, a spring-actuated lift-dog slidably arranged in said casing having a portion extending therefrom, and means operated from the crank-shaft and engaging with said lift-dog for actuating said oscillatory igniting-stem, consisting of a collar *o* and a spring-dog connected with said collar, substantially as and for the purposes set forth.

4. In an explosive-gas engine, the combination, with a cylinder, crank-shaft, and piston, of a bearing device in one side of the cylinder, having tubular openings, a fixed or stationary igniting-stem in one of said openings, but insulated from said bearing, an oscillatory igniting-stem in the other of said openings in said bearing, contact-pieces connected with said stems, and means connected with said oscillatory igniting-stem for producing a rock motion of the same, consisting, essentially, of an arm or lever *u* having one end attached to the free end of said oscillatory stem, a downwardly-extending rod or link *t*, with which the opposite end of said arm or lever *u* is operatively connected, an oscillatory casing to which the lower end of said rod or link *t* is attached, a spring-actuated lift-dog slidably arranged in said casing having a portion extending therefrom, and means operated from the crank-shaft and engaging with said lift-dog for actuating said oscillatory igniting-stem, consisting, of a set of gears operated from the crank-shaft, a collar *o* on the hub of one of said gears, and a spring-dog connected with said collar, substantially as and for the purposes set forth.

5. In an explosive-gas engine, the combination, with a frame or support, a cylinder, crank-shaft, and piston, of a box or casing *x* pivotally connected with said frame or support, a lift-dog slidably arranged in said box or casing, having one end extending therefrom, a lifting means arranged to be brought in operative engagement with the free end of said lift-dog, an igniting or sparking device connected with said cylinder, and an operative connecting means between said igniting or sparking device and said box or casing *x*, substantially as and for the purposes set forth.

6. In an explosive-gas engine, the combination, with a frame or support, a cylinder, crank-shaft, and piston, of a box or casing *x*

pivotsly connected with said frame or support, a lift-dog slidably arranged in said box or casing, having one end extending therefrom, a lifting means arranged to be brought in operative engagement with the free end of said lift-dog, an igniting or sparking device connected with said cylinder, consisting, essentially of a bearing device in one side of the cylinder, having tubular openings, a fixed or stationary igniting-stem in one of said openings, but insulated from said bearing, an oscillatory igniting-stem in the other of said openings in said bearing, contact-pieces connected with said stems and means connected with said oscillatory igniting-stem for producing a rock motion of the same, consisting, essentially, of an arm *u* having one end attached to the free end of said oscillatory stem, a downwardly-extending rod or link *t*, with which the opposite end of said arm or lever *u* is operatively connected, and said rod or link *t* having its lower end pivotally connected with said box or casing *x*, substantially as and for the purposes set forth.

7. In an explosive-gas engine, the combination, with a frame or support, a cylinder, crank-shaft, and piston, of a box or casing *x* pivotally connected with said frame or support, a lift-dog slidably arranged in said box or casing, having a lifting end extending therefrom, a lifting means arranged to be brought in operative engagement with the said lifting end of said lift-dog, a screw-threaded rod connected with said dog extending from the opposite end of said box or casing *x*, a finger-piece on said rod and an adjusting pin or stem on said finger-piece for varying the degree of extension of said lift-dog from said box or casing, an igniting or sparking device connected with said cylinder, and an operative connecting means between said igniting or sparking device and said box or casing *x*, substantially as and for the purposes set forth.

8. In an explosive-gas engine, the combination, with a frame or support, a cylinder, crank-shaft, and piston, of a box or casing *x* pivotally connected with said frame or support, a lift-dog slidably arranged in said box or casing, having a lifting end extending therefrom, a lifting means arranged to be brought in operative engagement with the said lifting end of said lift-dog, a screw-threaded rod connected with said dog extending from the opposite end of said box or casing *x*, a finger-piece on said rod and an adjusting pin or stem on said finger-piece for varying the degree of extension of said lift-dog from said box or casing, an igniting or sparking device connected with said cylinder, consisting, essentially, of a bearing device in one side of the cylinder, having tubular openings, a fixed or stationary igniting-stem in one of said openings, but insulated from said bearing, an oscillatory igniting-stem in the other of said openings in said bearing, contact-pieces connected with said stems, and means connected with said oscillatory igniting-stem for pro-

- ducing a rock motion of the same, consisting, essentially, of an arm *u* having one end attached to the free end of said oscillating stem, a downwardly-extending rod or link *t*, with which the opposite end of said arm or lever *u* is operatively connected, and said rod or link *t* having its lower end pivotally connected with said box or casing *x*, substantially as and for the purposes set forth. 5
9. In an explosive-gas engine, the combination, with igniting or sparking means, and a connecting arm or lever *u*, of a rod or link *t* having a screw end *t'*, a sleeve *v* on said screw end, provided with an enlargement *v'* forming a support for a ring-shaped end of said arm or lever *u*, a nut *v⁴* on the upper end of said sleeve, and a collar *v³* on said sleeve, above the ring-shaped end of said arm or lever *u*, and a spring encircling said sleeve *v* between said nut and collar on said sleeve, substantially as and for the purposes set forth. 10
10. In an explosive-gas engine, the combination, with igniting or sparking means, and a connecting arm or lever, *u*, of a rod or link *t* having a screw end *t'*, a sleeve *v* on said screw end, provided with an enlargement *v'* forming a support for a ring-shaped end of said arm or lever *u*, a nut *v⁴* on the upper end 15 of said sleeve, a collar *v³* on said sleeve, above the ring-shaped end of said arm or lever *u*, a spring encircling said sleeve *v* between said nut and collar on said sleeve, and a box or casing *x* with which the lower end of said rod or link *t* is pivotally connected, a lift-dog slidably arranged in said box or casing, having a lifting end extending therefrom, and a lift means arranged to be brought in operative engagement with the said lifting end of said lift-dog, a screw-threaded rod connected with said dog extending from the opposite end of 20 said box or casing *x*, a finger-piece on said rod, and an adjusting pin or stem on said finger-piece for varying the degree of extension of said lift-dog from said box or casing *x*, substantially as and for the purposes set forth. 25
- In testimony that I claim the invention set forth above I have hereunto set my hand this 16th day of December, 1899.
